UNITED STATES PATENT OFFICE.

ALVIN V. ROWE, OF GALESBURG, ILLINOIS.

GATE-HINGE.

1,192,120.

Specification of Letters Patent. Patented July 25, 1916.

Original application filed August 15, 1912, Serial No. 715,292. Divided and this application filed June 1, 1914. Serial No. 842,002.

To all whom it may concern:

Be it known that I, ALVIN V. ROWE, a citizen of the United States, a resident of Galesburg, in the county of Knox and State 5 of Illinois, have invented new and useful Improvements in Gate-Hinges, of which the following is a specification.

My invention relates to improvements in gate hinges, the principal object being the 10 provision of a two-part hinge member having extensions adapted to provide bracing and securing means for the hinge portion of the gate.

My invention has further reference to improvements in various details of structure, 15 arrangement and design of a hinge having particular application to that type of a gate which may be termed non-sagging.

To the accomplishment of the foregoing 20 and such other objects as may hereinafter appear, my invention consists in the construction, combination and arrangement of parts hereinafter described and then sought to be defined in the appended claims, reference being had to the accompanying drawings 25 forming a part hereof and which show, merely for the purpose of illustrative disclosure, one embodiment of my invention, it being understood however, that various 30 changes may be made in practice within the scope of the appended claims without digressing from my inventive idea which is defined herein.

In the drawings:—Figure 1 represents a 35 side elevation of a part of a gate equipped at the top with one form of my invention of hinges and at the bottom with another form of my invention in hinges; Fig. 2 is a side elevation of the upper corner portion 40 of the gate showing the hinge, this view being enlarged; Fig. 3 is a top plan view thereof; Fig. 4 is a section taken on the line 4—4 of Fig. 3. Fig. 5 is a plan view of part of 45 the lower hinge construction, and Fig. 6 is a side elevation thereof.

Referring now to the drawings, the numeral 1 designates the longitudinal members or slats being spaced apart and secured in proper relative position by the cross-pieces 2, which as shown preferably take the 50 form of angle irons. These angle iron cross-pieces are arranged in pairs on opposite sides of the boards and are connected by means of bolts 3.

The primary truss member is formed by 55 the diagonally disposed brace members 4 and 5 which are arranged in duplicate on opposite sides of the gate and secured together, constituting what might be called a double truss. These members are connected 60 together in the center of the middle pair as at 6, this having the advantage of making the gate self squaring, that is in assembling, permitting the members to be placed in proper position without the necessity of 65 squaring them up. As shown these brace members 4 and 5 are attached to the extremal portions of the end cross-piece 2, as at 7. The hinge members for the top and bottom 70 of the gate, indicated generally as 8 and 9, are provided with the extensions 10 and 11, to which the braces 4 and 5 are connected, as at 12 and 13. The end cross-piece 2 has the upwardly extending flange of the angle iron cut away as at 14 to provide the recesses 15 in which the hinge members 8 and 9 are seated, the latter being secured to said 75 end cross-piece 2 by means of the bolts 16 and 17.

Attention is now called to the particular 80 form of hinge disclosed in this application. I find it advantageous to provide a divided hinge for the purpose of permitting its use with lumber of different sizes. It may be stated here that these articles may be sold 85 not only as part of a complete gate structure, but also separately, the customer furnishing the lumber and assembling the gate. This is one of the reasons for the necessity 90 of furnishing adjustable hinge members. I show two forms of hinge members which are divided and consequently adjustable for different size lumber and will proceed to describe the first form.

This hinge member 8 is the top hinge 95 member illustrated in Fig. 1 and which is shown in detail in Figs. 2, 3 and 4. It is made in two parts 18 and 19, which parts are provided with the similar oppositely disposed extending portions 10 as shown. 100 These extending portions are provided with the shoulder or abutment 20 which is adapted to rest against the end of the angle iron cross-piece 2 as shown. Each of these members is further provided with the semi-circular or curved bearing or receiving portions 21 and 22 which cooperate to provide 105 a pintle receiving opening 23. These mem-

bers 18 and 19 are hinged together at their ends, the member 18 being provided with the pintle 24 and the opening 25 to receive the end of the curved member or finger 26 on member 19 which extends through the opening and engages the pintle 24. These members 18 and 19 are further provided with the shoulders or abutments 27 and 28 to engage the end of the longitudinal board or slat as shown. These shoulders or abutments are provided with interlocking members, the member 18 having the projections or extensions 29 near the top and bottom thereof and the member 19 having the extensions 30 adapted to fit in between the extensions 29 of said member 18. This form of hinge may be used as either a top or bottom hinge or both. I have illustrated it in use as a top hinge and have provided means for preventing the gate from being raised accidentally or by means of animals. This locking means comprises the downwardly extending members or lugs 31 which are provided with the extensions or shelves 32 which coöperate to produce a seat for the locking flange 33 which is formed on the lag screw 34 at the base of the pintle 35. This locking flange extends only from one end of the lag screw and not on the side thereof so that when the gate is shut it will be securely locked down, but when the gate is open and in a position approximately at right angles to its closed position, it may be raised from off said pintle.

35 The other form of hinge, illustrated as the lower hinge in Fig. 1 and also in detail in Figs. 5 and 6, has the advantage of being a divided hinge and therefore adjustable, and further has each member the same as 40 the other so that one pattern will serve to make the two parts of the hinge. As stated before these hinge members 9 have the extensions 11, provided with the shoulders or abutments 36 to bear against the end of the 45 angle iron cross-piece 1 and with the semi-circular or curved portions 37 which coöperate with each other to produce the pintle receiving portions 38. Each hinge member has the shoulder or flange 39 to bear against 50 the end of the longitudinal board or slat, each shoulder or flange being provided with the extensions and recesses similar to 29 and 30, adapted to interlock and hold the members of the hinge together. The two portions 55 are hinged together by providing at the end of each member an outstanding flange 42 with an opening 43 adjacent said flange. The other portion of each hinge member is provided with the extension 44 60 which has its extremity turned at approximately right angles to provide the locking member 45, this extension passing through the opening 43 and being positioned on the outside of said flange 42. This produces a 65 hinged relation between the two members

forming the hinge member and also provides a locking means preventing their dissembling.

It is therefore seen that I have provided a hinge member, in two forms, each hinge member being divided into two parts connected together in hinged relation and with interlocking means whereby they may be conveniently and positively positioned and held in position.

Attention is called to the fact that on the extensions of the two parts 18 and 19 of the upper hinge member 8, are provided a plurality of apertures whereby the hinge members may be readily secured in proper relation to the bracing means on gates of different sizes, it being obvious that in gates of various sizes, the inclination of the bracing members relative to each other and to the hinge members will vary. This provision of a plurality of apertures is for the purpose of rendering the hinge members readily attachable to any of the standard sizes of gates. It is to be noted that the lower hinge members are also provided with a plurality of apertures for the same purpose.

This application is a division of application filed August 15th 1912, bearing Serial No. 715,292.

What I claim is:

1. In a gate, a hinge formed of two parts or members, each part or member being extended to provide a brace or truss member adapted to extend along the sides of the gate, each part or member having a pintle receiving portion corresponding with a similar portion on the other part or member and adapted to form a pintle receiving opening therewith, said parts or members being provided with means whereby they may be pivotally connected together at their outer ends, said extensions of said parts or members of the hinge being provided with a plurality of apertures adapted to receive the securing means so that the hinge member may be used with different sized gates.

2. A gate hinge including a two-part member having extensions adapted to be secured to the sides of the gate, each part having a semi-circular recess, which recesses complement each other to provide the pintle receiving openings, said parts being hinged together at their ends on the side of said pintle receiving opening away from the end of the gate, each part also having shoulders adapted to engage the end of the gate, said shoulders being provided with interfitting portions.

3. A gate hinge including a two-part member having extensions adapted to be secured to the sides of the gate, each part having a semi-circular recess, which recesses complement each other to provide the pintle receiving openings, said parts being hinged together at their ends in the side of said

pintle receiving opening away from the end of the gate, each part also having shoulders adapted to engage the end of the gate, said shoulders being provided with interfitting portions, said interfitting portions including projections near the top and bottom of one of said parts and intermediate projec-

tions adapted to fit between said first mentioned projections on the other part.
